DESIGN FOR A SPOON HOLDER

Thomas I. Frissell, Rock Creek, Ohio

Application May 18, 1939, Serial No. 85,068

Term of patent 3½ years

To all whom it may concern:

Be it known that I, Thomas I. Frissell, a citizen of the United States, and a resident of Rock Creek, county of Ashtabula, and State of Ohio, have invented a new, original, and ornamental Design for a Spoon Holder, of which the following is a specification, reference being had to the accompanying drawing, forming a part thereof.

In the drawing:

Fig. 1 is a top plan view of the spoon holder, showing my design;

Fig. 2 is a side elevational view thereof; and Fig. 3 is a perspective view of the spoon holder showing its appearance when it is applied to a culinary vessel, it being understood that the culinary vessel fragmentarily shown in dotted lines forms no part of the design, being used for illustrative purposes only.

I claim:

The ornamental design for a spoon holder, as shown and described.

THOMAS I. FRISSELL.
